UNITED STATES PATENT OFFICE

JOHANNA ELSIE ASTER, OF NEW YORK, N. Y.

CIGAR AND CIGARETTE HOLDER, AND SIMILAR ARTICLE

Application filed March 12, 1927. Serial No. 174,758.

This invention has to do with cigar and cigarette holders, pipes, and similar articles used by smokers.

It is an object of the invention, in one of its embodiments, to provide a device of this kind by the use of which the operations of smoking may be performed either in the usual way, so far as expulsion of smoke from the mouth is concerned, or in an unexpected way 10 which, as will appear hereinafter, may readily be made to furnish amusement. To this end I provide a construction such that the smoke drawn into the mouth may if desired be expelled through a special smoke-dis- 15 charged orifice in the device; and this orifice may be controlled either manually or by means of a check-valve. Where a check- valve is employed it may take a particular form; for instance, the cigarette or tobacco 20 holding part of the device may be in the form of a comic head, the smoke discharge orifice may be the nose thereof, and the check- valve a tongue which is retracted into the head to close the discharge opening when 25 smoke is drawn in, and is projected from the head, incidentally opening the smoke discharge orifice, as the smoker expels smoke.

Another feature of the invention, which may be utilized conjointly with or independ- 30 ently of the constructions above mentioned, is the provision of independent sockets or receivers for a plurality of cigarettes, cigars, or tobacco charges.

Other objects and characteristics of the 35 invention will appear in the course of the following description of the elements, combi- nations, and arrangements of the parts con- stituting the invention, and the scope of protection contemplated is indicated in the 40 claims.

In the accompanying drawings, in which I have shown preferred forms of the invention:

Fig. 1 is a perspective view illustrating my 45 device, as a cigarette holder, in use;

Fig. 2 is a view of the cigarette holder of Fig. 1, partly in side elevation and partly in vertical longitudinal section;

Fig. 3 is a front elevation of the same;

Fig. 4 is a longitudinal vertical section of

the device, with the mouth-piece or bit bro- 5 ken away, showing a simple check-valve for controlling the smoke orifice;

Fig. 5 is a view similar to Fig. 4, illustrating a special form of check-valve; and 55

Fig. 6 is a view similar to Fig. 3, but illustrating two cigarette sockets or receivers.

Referring to the numerals on the drawings, there is shown at 7 a tube like that of an ordinary cigarette holder, or like the stem of a 60 tobacco pipe. This tube or stem terminates at one end in a receiver 8 for the cigarette or other smokable material or charge. This receiver may be shaped and or decorated to represent a comic face, human or animal or 65 fanciful, with, for instance, a nose opening (or openings) 9 and a preferably upwardly extending cigarette receiving socket 10. It is obvious that with a lighted cigarette in place, as in Fig. 1, if the opening 9 is covered by the finger, smoke may be drawn into the mouth of the smoker through the tube; and that, if the opening 9 be now uncovered, smoke may be expelled through the tube so that it will issue out of the orifice 9. This 70 opening may be a representation of a mouth, a nose, or one or more eyes or ears, according to the fancy of the designer. The essential feature is that the device has a controllable smoke discharge orifice in communication 75 with the tube, in addition to the cigarette receiving socket.

In Fig. 4 the smoke discharge orifice is automatically controlled by a simple check valve 11, hinged at 12, so that it closes the orifice 13 when suction is exerted through the tube, in the act of drawing smoke into the smoker's mouth, and opens when smoke is expelled from the smoker's mouth through the tube. 85

In the Fig. 4 structure the cigarette-receiving part of the device is made in two parts, united along the parting line 14 to facilitate manufacture, in particular the fitting of the check-valve to the other parts. 90

In Fig. 5 the smoke discharge orifice is sup- 95 posed to be a nasal opening, and the check- valve, controlling the inner end of this orifice, is a flexible piece of rubber 15 fastened at its edges inside and near the outer end of a mouth-like passage 16, the rubber piece be- 100

ing of such size and flexibility that it may assume the reverse positions shown in full lines and dotted lines respectively in Fig. 5, accordingly as there is suction or outward pressure in the tube. In the one case the tongue is drawn back into opening 15, closing off the orifice 9; in the other case the tongue is projected out of the mouth opening 16, simultaneously with the opening of and discharge of smoke from, the nasal opening 9. At all times, of course, the mouth 16 is closed against outlet of smoke or inlet of air. The check-valve may of course be in the form of a movable ear, or nose, or eye-brow, and the device may be furnished with one or more of such movable members which do not have the check-valve function. For instance, referring to Fig. 5, the rubber tongue 15 might be not long enough to close off the orifice 9 when retracted, the latter being either manually controlled (Figs. 1 and 2), or provided with a separate check-valve.

In Fig. 6 I show the head of the device provided with two diverging cigarette sockets, both in communication with the tube. This arrangement may be used with or without the separate smoke orifice, check-valve, &c.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the invention which, as a matter of language, might be said to fall therebetween.

I claim:—

45 1. An article of manufacture comprising a tube, a terminal having formed therein a socket for receiving a charge of smokable material, said socket being in communication with the tube, the terminal member being provided with a smoke discharge passage opening into the tube, the exterior of the terminal member being provided with a representation of a face having facial orifices, the outer end of the smoke discharge coinciding with a facial orifice.

2. An article of manufacture comprising a tube, a terminal having formed therein a socket for receiving a charge of smokable material, said socket being in communication with the tube, the terminal being provided with a smoke discharge passage opening into the tube, the exterior of the terminal member being provided with a design, a valve member mounted on the terminal and controlling the smoke discharge passage, the

valve member being visible from the exterior of the terminal member and constituting part of the design.

3. An article of manufacture comprising a tube, a terminal having formed therein a socket for receiving a charge of smokable material, said socket being in communication with the tube, the terminal being provided with a smoke discharge passage opening into the tube, the exterior of the terminal member being provided with a representation of a face having facial orifices and members, the outer end of the smoke discharge passage coinciding with a facial orifice, a valve member mounted on the terminal, said valve member controlling the smoke discharge passage and being a representation of a movable facial member.

4. An article of manufacture comprising a tube, a terminal having formed therein a socket for receiving a charge of smokable material, said socket being in communication with the tube, the terminal being provided with a smoke discharge passage opening into the tube, the exterior of the terminal member being provided with a representation of a face having facial openings, the outer end of the smoke discharge passage coinciding with a facial orifice, a valve member mounted on the terminal, said valve controlling the smoke discharge passage and being a representation of a movable tongue.

5. An article of manufacture comprising a tube, a terminal having formed therein a socket for receiving a charge of smokable material, said socket being in communication with the tube, the terminal being provided with a smoke discharge passage opening into the tube, the exterior of the terminal member being provided with a representation of a face having a mouth and nasal openings, the smoke discharge passage registering with the mouth, the nasal openings being in communication with the smoke discharge passage, and a movable valve member in the mouth and controlling passage of smoke through the nasal openings, said valve member being a representation of a movable tongue.

In testimony whereof I affix my signature.

JOHANNA ELSIE ASTER.
